UNITED STATES PATENT OFFICE.

OTTO SCHALLER, OF SÜDENDE, NEAR BERLIN, GERMANY.

ELECTRIC INCANDESCENT LAMP.

1,016,099.

Specification of Letters Patent.

Patented Jan. 30, 1912.

Application filed July 24, 1911. Serial No. 640,215.

To all whom it may concern:

Be it known that I, OTTO SCHALLER, a citizen of the German Empire, and residing at Südende, near Berlin, German Empire, 5 have invented certain new and useful Improvements in Electric Incandescent Lamps, of which the following is a full, clear, and exact description.

Hitherto the current feed from the outside 10 to the filament in electric incandescence lamps has been effected by means of thin wires, fused in the glass walls of the bulbs. Platinum wires were generally employed for this purpose or wires of other metal, the 15 coefficient of expansion of which was approximately the same as that of the glass, in order, as far as possible, to avoid leakage at the points of fusion and consequent cracking of the glass on the alternate heating and cooling of the bulbs and the feed 20 wires.

Apart from fusing in the feed wires, attempts have been made to effect a reliable sealing of the feed wires by means of packing, such as impregnated paper or rubber or varnish coating, but in connection with all these substances, the unavoidable variations of temperature inevitably resulted in leakage, due mainly to the fact that the 25 surfaces to be sealed, even in the case of conical seals, were always surfaces lying in the longitudinal direction of the wires or current feed to be sealed. In connection with this class of current feed, it is quite impossible, 30 to entirely prevent differences of tension between the feed wires and the material surrounding the same on expansion and contraction due to differences of temperature—especially if the wires are somewhat thick,— 35 40 which differences of tension result in leakage due to cracks produced and the consequent entrance of air into the bulb.

According to the present invention the sealing of the conductors to be introduced 5 into the lamp is attained, in contradistinction to those methods hitherto known, by means of surfaces situated laterally of the feed wires, which contact with corresponding sealing surfaces of the glass bulb or of 10 insulating devices. These sealing surfaces, which may be of any desired size compatible with the size of the lamps, render it possible to keep the current feed wires themselves

in tight connection with the lamp, *i. e.* the bulb, solely by means of the atmospheric air 55 pressure, which, in its turn again, enables the contacting sealing surfaces to move one on the other, on varying expansion or contraction of the materials of which they consist. The expansion or contraction of the 60 current feeds and the contacting materials will show but very slight displacement in the registering sealing surfaces. Grease or a liquid packing material may be inserted between the sealing surfaces, which are advantageously ground on each other, in order 65 to insure an air tight contact of the surfaces. In connection with these sealing surfaces extending laterally of the current feed conductors, any known sealing medium may 70 be employed, such for instance as rubber or paper, which may be impregnated, or any known liquid or labyrinth packing. All these sealing devices need only possess the 75 slightest elasticity, since the difference of expansion of the lamp materials in question is of the slightest. The laterally extending sealing surfaces, which may be arranged on terminals, wires, rods, enable also the employment of current conductors of any 80 desired diameter, so that high pressure current lamps may be employed, without any restriction 85 as regards the strength of current.

In the accompanying drawing some embodiments of the invention are illustrated. 85

Figure 1 is a vertical section showing a simple form of the invention, Fig. 2 is a similar section of a lamp for alternating current, Fig. 3 is a part section drawn to a larger scale of a liquid seal, Fig. 4 is a 90 vertical section showing the conductor in the form of a plate and Fig. 5 shows the arrangement of contacting surfaces not applied directly to the bulb.

In Fig. 1 the body of the lamp consists 95 substantially of a spherical glass or quartz bulb *a* having two necks *b* and *c*, the upper edges of which are advantageously ground. On to these surfaces are fitted the current feed conductors *d* and *e* by means of their 100 plate-like advantageously ground enlargements *f* and *g*. To the parts of the feed conductors, which extend into the bulb *a*, the incandescence body *h* is screwed or welded, which body may consist of several wires, 105 rods, bows or plates. This attachment may

be effected by first introducing the incandescence body through one of the openings *b* or *c* into the lamp and then pushing both ends through their respective openings far enough out of the lamp, to effect the connection with the current feed conductors outside the lamp. These lamps may be worked with continuous or alternating current.

In Fig. 2 a lamp is illustrated, which is adapted for alternating current. In this case the feed conductors *d* and *e* are conductively connected by means of a bow *i*. This bow may be rigid or elastic, solid or divided, may consist of one or several windings and may be in one piece with the current feed conductors or rigidly or detachably combined with the same. The attachment of the incandescence body *h* is shown at the terminal *d* by means of a screw, while at *e* it is welded on. The attachment may be effected in any desired manner. This form of attachment may be carried out in that the bulb *a* is divided at some point *k*. The lower part is then connected to the other part after the incandescence body has been attached and the parts may either be fused together or, may be held together by air pressure when the lamp is evacuated, in which case all the devices, necessary for the current feed by means of air pressure, may also be utilized for this air tight connection of the two parts of the bulb. This lamp is glowed by induction, in that an alternating field is taken through the bow *i*, advantageously by means of an iron core *p*. If the bow *i* is detachably arranged, this lamp may be easily converted into one like that illustrated in Fig. 1, for continuous and alternating current. Clamps *l* are provided at the contacting surfaces *c* and *g*, which are intended to prevent the bulb from falling off, in the event of air penetrating to the interior of the lamp. Other devices may also serve the same purpose, such as chains, wire baskests, protecting nets or outer globes. The point of connection *k* may also be provided with like or similar safety devices. A labyrinth packing *m* is provided between *f* and *b* having several packing rings, while liquid seals having flutings or grooves are illustrated between *g* and *c*. A liquid seal between *b* and *f* is illustrated in Fig. 3 in detail, showing grooves *n* and projections *o* extending down into the liquid filling the grooves.

In the embodiment illustrated in Fig. 4 the conductor connecting the current feed is developed in the form of a plate *q*, while the magnetic alternating field is generated in the space *p*, left free between the correspondingly prolonged necks *b* and *c* of the bulb *a*. The feed conductors *d* and *e* may be made in one piece with the part *q*. Their connection with the incandescence body *h*

may be effected in the same manner as that described with reference to Fig. 1. In this case also safety clamps *l* are provided, while the sealing of the contacting surfaces is assisted in this case for instance, by means of a packing medium *r*. It is not necessary that the contacting surfaces, at which the feed conductors are air tightly connected to the lamp, by means of the air pressure, are arranged on the bulb itself. This may be effected by means of one or more intermediate members, which may be attached to the bulb in suitable manner.

Fig. 5 illustrates an example of this form of the invention. The feed conductors *e* *d* are mounted with their lateral sealing surfaces on an insulating plate *t*, which may consist of any insulating material. The reliability of seal may be augmented by means of overlapping flanges, or grooves. After the incandescence body *h* has been attached to the feed conductors *d* *e*, the plate *t* is placed on the bulb, on to which it is pressed by the evacuation of the latter. If the material chosen for the plate *t* does not offer sufficient resistance to the air pressure, or is not suitable to form a seal with the edge of the bulb, a plate *u* of suitable material—such for instance as glass or metal may be interposed, in which case, however, it must be insulated as regards the feed conductors. Then the seal between *a* and *u* will be secured, while the seal between *u* and *t* will not present much difficulty in view of the large size of the surface, more especially if the labyrinth form of packing is employed. In this case the sealing surfaces of the feed conductors will be held tight by the air pressure in the above described manner, at the plate *t* and thus with the lamp. In order to attain like phases or conductor loads, when two or multiple phase current, or multiple wire continuous current is employed, incandescence bodies may be employed having two or more branches and each branch may be provided with a current feed. The bulbs according to Figs. 1, 2 and 4 may then be provided with three or more necks.

I claim as my invention:

1. In an incandescent electric lamp, a globe having a part provided with openings for the feed conductors, said part having transversely disposed bearing surfaces around said openings, and feed conductors having transversely extending bearing surfaces corresponding to said first named bearing surfaces, said parts being held together solely by atmospheric pressure.

2. An incandescent electric lamp comprising a globe having transversely arranged plain flat surfaces, and feed conductors having corresponding plain flat surfaces, said parts being held together solely by atmospheric pressure.

3. An incandescent electric lamp comprising a globe having transversely arranged plain flat surfaces, feed conductors having corresponding transversely extending bearing surfaces, and a liquid seal interposed between said bearing surfaces, said parts being held together solely by atmospheric pressure.

In testimony whereof I affix my signature in the presence of two witnesses.
